CLAIM

The ornamental design for a fuel tool enclosure, as shown and described.

DESCRIPTION

FIG. 1 is a side perspective view of the fuel tool enclosure in its closed position;

FIG. 2 is another side perspective view thereof;

FIG. 3 is a perspective view of the second or other side thereof;

FIG. 4 is a front perspective view thereof;

FIG. 5 is a back perspective view thereof;

FIG. 6 is a top view thereof;

FIG. 7 is a bottom view thereof; and,

FIG. 8 is a side perspective view of the fuel enclosure in its open position.

The broken lines are included for the purpose of illustrating environmental structure and form no part of the claimed design. Indeterminate length is shown by illustrating a separating break to indicate that although the claimed design has uniform shape and appearance throughout its length, the precise length of the enclosure is not claimed.
